UNITED STATES PATENT OFFICE.

EDWARD B. HESS, OF NEW YORK, N. Y., ASSIGNOR TO ROYAL TYPEWRITER COMPANY, OF HOBOKEN, NEW JERSEY, A CORPORATION OF NEW JERSEY.

WRITING-MACHINE.

No. 856,870.

Specification of Letters Patent.

Patented June 11, 1907.

Application filed September 1, 1906. Serial No. 332,940.

To all whom it may concern:

Be it known that I, EDWARD B. HESS, a citizen of the United States, residing in the borough of Brooklyn, city and State of New York, have invented certain new and useful Improvements in Writing-Machines, of which the following is a specification.

This invention relates primarily to type-bar actuating devices, particularly those for front strike machines, whereby the touch of the keys improved and the several type-bars returned with celerity from the impression point.

Figure 1 is a longitudinal vertical sectional view illustrating the application of return springs to the type-bars; Fig. 2, a similar view showing the key lever partly depressed and the type-bar as having passed through the major part of its excursion to the printing point; Fig. 3, a like view showing the type-bar at the printing point; Fig. 4, a diagrammatic plan view illustrating a series of type-bar springs and the two end bars of the series of type-bars; Fig. 5, a detail view of one of the type-bar springs of the kind shown in the foregoing figures.

The springs acting to retract the several type-bars from the printing point are so disposed, constructed or arranged that they are placed under tension only after the type-bar has completed the major part of its excursion to the printing point and is therefore more or less adjacent to such point: and preferably the springs come into action only after the universal bar of the machine has been set in motion.

A type-bar spring behaving in this way is indicated in Figs. 1, 2 and 3, in which *a* indicates the usual cylindrical rotatable platen. The spring *r* is shown as attached to the heel of the type-bar outside of the point of connection thereto of the type-bar actuating link *o*², the spring extends rearwardly and the metal of which it is composed is, beyond the convolutions of the spring, extended rearwardly in a straight line through an aperture in a vertical plate *s* and is provided with an enlargement or stop at its end. In the normal position shown in Fig. 1 the rear spring portion of the spring wire is projected a material distance through the aperture in the plate. Consequently, when the key lever is depressed and the type-bar moved to-

ward the printing point, the spring is not placed under tension until the enlargement 55 or projection *r*¹ abuts against the rear face of the plate. This position of the parts is indicated in Fig. 2. As the type-bar continues its movement to the printing point, the spring *r* is placed under tension as shown 60 in Fig. 3 and, by its reaction, quickly draws the type-bar from the printing point when the finger piece is released.

Fig. 4 shows a series of springs arranged in trough-like formation, conforming generally to the curve of the type-bar segment. They are all formed with straight rearward extensions which each pass through an aperture in the plate *s* and at the extreme rear end the wire is double curled, into two eyes, 70 forming a stop or limiting head *r*¹, or as shown in Fig. 5, an adjustable head *t* may be fixed upon the wire of the spring at any desired point by means of a set screw and operates as a stop contacting with the rear 75 face of the plate *s* to limit the free forward movement of the spring. The distance between the heels of the type-bars and the plate *s* in a machine of the general character illustrated may be such that the coiled parts 80 of the several springs may be staggered and yet each be perfectly free in its movement. Thus the convolutions of one spring are arranged alongside of the straight part of the wire of the adjacent spring. This permits of 85 the springs being placed in a space equal in width with the length of a line connecting the heels of the two outer type-bars.

The springs *u* applied to the front links *v* of each type-bar actuating connection may be 90 a relatively light one and serves primarily to retain the bar against its back rest. The type-bar springs *r* act also to insure disengagement of the bars from the type-bar guide should there be any tendency for the 95 bars to stick therein. A type-bar guide of ordinary construction is indicated at *d*, Fig. 1.

A type-bar spring, having the general mode of operation described and falling within this invention considered in its 100 broader aspects, may no doubt be constructed and arranged differently from those illustrated without departing from the principles of this invention.

Type bar springs performing the function 105 of those herein described might be placed in

front of the type-bar pivots, being in that case attached to the bars above their pivots.

I claim as my invention:

1. In a typewriting machine, a coiled spring for actuating a type-bar, normally under no tension and extended and under tension as the type-bar reaches the printing point.
2. In a typewriting machine, a spring for actuating a type-bar being slidable or movable longitudinally and also elastically extensible longitudinally.
3. In a typewriting machine, a type-bar spring longitudinally elastic and having a slidable portion integral with the elastic portion.
4. In a typewriting machine, a spring permanently in connection with the type bar and exerting no force on the retraction of a type-bar during its travel except adjacent to the printing point.
5. In a typewriting machine, a spring directly applied to the type-bar having both a sliding and extending movement as the type-bar approaches the printing point and a sliding and contracting movement as it recedes from the printing point.
6. In a typewriting machine, the combination of pivoted type-bars and a spring for each type-bar to retract it from the printing point and at all times connected to the heel of the type-bar and moving therewith but exerting no influence on the return movement of the bar except adjacent to the printing point.
7. In a typewriting machine, the combination with a type-bar of a slidable and extensible spring located behind the pivot of a type-bar.
8. In a typewriting machine, the combination with a series of pivoted type-bars of a series of slidable and extensible springs lying in segmental form and adapted to facilitate the return of a series of type-bars.
9. In a typewriting machine, a type-bar combined with a spring arranged with a plain portion on either end and a spiral portion between the plain portions and having one end secured to the type-bar and the other end slidable adjustably against a stop.
10. In a typewriting machine, a type-bar combined with a retracting spring moving when the type-bar moves but exerting no

tension on the type-bar until it is adjacent to the printing point.

11. In a typewriting machine, a type-bar and a spring therefor which latter moves as the type-bar moves but exerts its influence on the type-bar during a portion only of its excursion to and retreat from the printing point.

12. In a typewriting machine, the combination of a series of pivoted type-bars and series of staggered coiled springs which exert no tension on the type-bars until the latter approach the printing point, the coil of each spring being opposite a straight portion of the wire of adjacent springs.

13. In a typewriting machine, the combination with a type-bar of a spring for actuating it and both ends of which move at the same time throughout the major portion of the travel of the bar to the printing point.

14. In a typewriting machine, the combination of a type-bar, a type-bar guide at the printing point, and a type-bar retracting spring brought into effective action during the latter part only of the advance movement of the type-bar.

15. In a typewriting machine, the combination with a type-bar and a slidable extensible spring located behind the pivot of the type-bar and placed under tension during the latter part only of the advance movement of the type-bar of a type-bar guide located adjacent the printing point.

16. In a typewriting machine, a type-bar combined with a retracting spring moving when the type-bar moves but exerting no tension on the type-bar until it is adjacent to the printing point and a type-bar guide adjacent the printing point.

17. In a typewriting machine, the combination of a type-bar, a type-bar actuating device acting under tensile strain to pull the type-bar to effect the printing stroke, and a spring placed under tensile strain during the latter part only of the stroke of the type-bar and acting to pull it away from the printing point.

In testimony whereof, I have hereunto subscribed my name.

EDWARD B. HESS.
